SIGN

Alan Metreger, Chicago, Ill., assignor to Safety Signs, Inc., Chicago, Ill., a corporation of Illinois

Application February 25, 1939, Serial No. 258,495

2 Claims. (Cl. 40—135)

This invention relates to signs and more particularly to reflecting signs that are intended to have a high visibility by daylight and have high light reflecting properties so as to render them highly visible by reflected light as from the headlights of an approaching automobile.

Construction work on highways is fraught with danger both to the men working on the highway and to approaching motorists. It is customary to erect signs on or adjacent the road at a distance from the place where the work is progressing or where the road has been rendered impassable or dangerous, said signs depending upon reflection of light from the headlights of approaching vehicles to render them visible. It is essential that such signs have very high reflecting properties so that they may be visible from a great distance. It is also essential that such signs be reliable in their action and not subject to rapid deterioration by the weather.

It is an object of the present invention to provide a sign which may be placed on or adjacent a highway to warn motorists of the dangerous condition ahead, which sign shall be reliable in its action, shall be weather-proof, water-tight, and not subject to deterioration by sunshine, wind, hail, snow, sleet, or the like. It is a further object of the present invention to provide such a sign wherein the words, or other signal indicia to be conveyed, are capable of reflecting a large amount of incident light from the headlights of approaching vehicles and wherein the background of said indicia also has high reflecting properties. The indicia and the background are made of distinctly different colors, as, for instance, white or silver colored indicia on an intensely red background, where both the white or silver color and the red are of very high reflecting properties. It is a further object of the present invention to provide a sign of the above character having a transparent water-proof cover which is not affected by sunshine, rain or sleet, and which can be removed and replaced in the event of mechanical injury to said cover. It is a still further object of the present invention to provide a sign which is economical of construction and may be easily and quickly mounted in place.

The attainment of the above and further objects of the present invention will be apparent from the following specification taken in conjunction with the accompanying drawing forming a part thereof.

In the drawing:

Figure 1 is a front view of a sign embodying the principles of the present invention with portions of the sign broken away to illustrate the construction thereof;

Figure 2 is an enlarged fragmentary sectional view taken along the line 2—2 of Figure 1 and looking in the direction of the arrows;

Figure 3 is an enlarged fragmentary perspective view of certain parts of the sign of Figure 1, the thickness of certain parts being greatly exaggerated for the sake of illustration; and

Figure 4 is an enlarged front view of the surface of the "letter forming" material.

Referring now more particularly to Figures 1 and 2, the sign of the present invention comprises a metal back 1 made, preferably, of sheet steel of any desired thickness as, for instance, 22 to 28 gauge in the preferred construction. A metal foil sheet 2 is adhesively secured to the front surface of the back 1. The metal foil sheet 20 consists of a paper sheet 3 having a suitable adhesive 4 at the back surface and having metal foil applied to the front surface thereof. The composite sheet 2 comprising the foil, paper, and adhesive 4 is of a thickness slightly in excess of 25 the thickness of a sheet of newspaper. The front surface of the foil 2 is preferably of a danger indicating color, such as red. The mucilage 4 is moistened with water and the sheet is pasted to the steel back 1. Individual letters 8, in the 30 present instance spelling out the word "Danger", are then pasted to the front of the metal foil sheet 2. The letters consist of a paper backing 10 surfaced at the front side with metal foil 8 and at the back with a suitable adhesive 11. The 35 entire thickness of the composite letter sheet 8 is slightly in excess of that of a sheet of ordinary newspaper. It is preferable that the metal foil of the letter 8 be of a color contrasting with the red color of the foil 2. The silver color is 40 suitable for the foil 8. The foil constituting the letters is of the type known as "Silver Circle Foil" and is characterized by the fact that the front surface of the metal foil has a very large number of adjacent small circles 12 formed 45 thereon, each circle having a large number of swirls 13 corresponding to the swirls formed in an ink fingerprint impression. These circles or swirls greatly facilitate the reflection of light from the foil 12.

It is difficult to maintain the letters 8 adhesively secured to the foil 2 by means of the mucilage or adhesive 11 at the back of the letters 8. To facilitate such holding action and to prevent separation of the letters from the foil 2, 55

especially at the corners of the letters, a sheet 15 is adhesively secured over all of the letters and over adjacent parts of the foil 2. The cover sheet 15 is colorless and transparent and comprises an acetate very similar to thin Celluloid. It is approximately 0.002 inch thick, is substantially fire-proof, and does not discolor under the action of sunlight for long periods of time. The cover sheet 15 is gummed at the back so that by moistening the back of this sheet it may be adhesively secured to the metal foil sheet 2. The cover sheet 15 maintains the letters of the sign flat against the foil 2 and seals the letters to the metal foil sheet 2.

15 Covering the entire front of the sign is a rather thick sheet 20 comprising a colorless transparent acetate similar to thin Celluloid except that it is fully transparent, does not appreciably contract or expand and is not affected by sunshine over long periods of time. This material is known in the trade as 10 point "Lumrith" or "Kodapak" and is of a thickness approximately 0.010 inch. The sheet 20 adds thickness or depth to the sign. After the sheet 20 has been placed in position the edges of the steel back 1 are bent forward and then downwardly to overlie the sheet 20, as indicated at 22, the edges being pinched downward to effect substantially a sealing action. Mounting eyelets 23 are then inserted in place.

Because of the two contrasting colors, both of high reflecting metal foil, the sign is easily discernible at an appreciable distance at night by the light of the headlights of an approaching automobile. At great distances only the red background of the sign is discernible which, of course, indicates danger. Slightly closer the insignia 8 appears black on a red background. At still closer distances, say approximately one-quarter to one-half of a block, the letters are discernible as bright silver or white letters by the light reflected therefrom.

The front surface of the sheet 2 is originally smooth. If it is desired to maintain a smooth front surface 2 in the finished sign the adhesive 4 is moistened sparingly and the excess water is pressed out before the adhesive 4 has bonded the sheet to the back 1. If a roughened front surface of the foil 2 is desired as indicated, that

result is obtained by eliminating the operation of pressing out the water between the sheet 2 and the back 1.

While I have herein described a sign that has a word formed thereon, it is to be understood that the silver circle foil need not necessarily be in the form of letters. It may, for instance, be in the form of a single arrow of silver circle foil on the red metal foil background 2, which red metal background need not be of octagonal 10 shape. It may also be in the form of a larger arrow.

While I have herein described my invention in the form of silver circle foil letters superimposed upon the red foil background, the reverse arrangement may be used if desired. The cover sheet 15 would also be used in such an arrangement.

In compliance with the requirements of the patent statutes I have here shown and described 20 a preferred embodiment of my invention. It is, however, to be understood that the invention is not limited to the precise construction here shown, the same being merely illustrative of the principles of the invention. What I consider new 25 and desire to secure by Letters Patent is:

1. A reflecting sign comprising a supporting back, a metal foil sheet adhesively secured to said back, metal foil insignia adhesively secured to said sheet, a transparent membrane covering 30 the insignia and adhesively secured to said metal foil sheet, a transparent cover for said membrane and foil, and means sealing the transparent cover and the back to form a closed envelope for said foil.

2. A reflecting sign comprising a supporting sheet metal back, a paper-backed reflecting foil sheet pasted on the metal back, paper-backed metal foil insignia pasted on the first mentioned foil and of a distinctly different color therefrom, 40 said insignia foil having corrugations in the form of swirls formed on the reflecting surface thereof, a membranous transparent sheet covering said insignia and pasted on said first mentioned foil, a flexible transparent cover sheet for said foil, 45 and means securing the cover sheet and supporting sheet together to form a closed envelope for the first mentioned foil sheet and the insignia.

ALAN METREGER.
